UNITED STATES PATENT OFFICE.

PETER D. PAULS, OF DENVER, COLORADO.

COMBINATION LIBRARY AND DRAWING TABLE.

1,193,417.

Specification of Letters Patent. Patented Aug. 1, 1916.

Application filed August 4, 1915. Serial No. 43,624.

To all whom it may concern:

Be it known that I, PETER D. PAULS, a citizen of the United States, residing at Denver, in the county of Denver and State of Colorado, have invented new and useful Improvements in Combination Library and Drawing Tables, of which the following is a specification.

This invention relates to articles of furniture, and in particular to a convertible table which is intended to be used either as a library table, or as a drawing table for use by draftsmen, architects, or the like.

The primary object of the invention is to provide a table of this character which is adapted normally to present the appearance of the ordinary library table and which may be used in this capacity, but whose top is movably mounted upon the supporting frame of the table in such a manner that it may be elevated and tilted to the desired degree by means provided for that purpose for convenient use in drawing and sketching.

A still further object is to provide adjusting means for the table top, which may be manipulated by the expenditure of a minimum amount of exertion, and which will serve to secure the top rigidly in adjusted position, but which may be released readily when it is desired to return the top to its normal position.

The invention consists in the features of construction, combination, and arrangement of parts, hereinafter fully described and claimed, reference being had to the accompanying drawings, in which:

Figure 1 is a front elevation of the table when arranged for library use with its top in its normal position; Fig. 2 is a side elevation of the same; Fig. 3 is a vertical sectional view on line 3—3 of Fig. 1; Fig. 4 is a side elevation of the table, showing the top elevated slightly and horizontally disposed with its cover open; Fig. 5 is a front elevation of the same; Fig. 6 is a vertical sectional view on line 6—6 of Fig. 5; Fig. 7 is a side elevation of the table, showing the top elevated and arranged in its regular inclined position for use in drafting; Fig. 8 is a rear elevation of the same; Fig. 9 is a vertical view on line 9—9 of Fig. 8; Fig. 10 is a side elevation of the table, showing the top arranged in one of its extremely inclined positions for use in sketching, the top being closed; Fig. 11 is a rear elevation of the

same; and, Fig. 12 is a transverse vertical sectional view on line 12—12 of Fig. 7.

In the drawings, the numeral 1 designates the frame of the table which may be constructed, as shown, like the usual form of library table. The upper, body portion of the frame, which is mounted upon the legs 2, includes the side rails 3, the front and rear rails 4 and 5 respectively, and the bottom 6. The movable top 7 of the table, which is rectangular in construction, is provided upon its under face with marginally arranged flanges 8, which latter are spaced inwardly from the edges of the top and are adapted normally to rest upon the rails of the body portion of the frame when the table is to be used for library purposes.

The table top is connected with the frame by means of a lazy-tongs device, each side portion of which includes the medially pivoted cross bars 9 and 10, which are connected by means of the pivot bolt 11. The lower ends of the bars 9 of both sets are pivotally connected with the side rails 3 of the body portion of the table frame inwardly thereof by means of the pivot pins 12. The lower ends of both bars 10, however, are connected by means of a transverse rod 13 and are adapted normally to bear upon the longitudinal ledges or tracks 14 provided upon the inner faces of the said side rails 3 immediately above the bottom 6.

The upper ends of the companion bars 9 are connected by means of a transverse rod 15 and are adapted to bear against the bottom of the table top, inwardly of its flanges 8. A transversely extending operating shaft 16 is journaled in the side portions of the top flanges 8 adjacent to the front edge of the top and the upper ends of the bars 10 are pivotally connected therewith, inwardly of the said flanges. Flexible members 17, which are preferably in the form of steel straps, are connected with the cross-rod 15 adjacent to the ends thereof and extend upwardly over a guide bar 18 which extends transversely beneath the top to the operating shaft, to whose ends they are connected in such a manner that they may be wound thereon.

The ends of the guide bar 18 are secured to a pair of strips 19 which extend along the under face of the table top in parallel relation to the side edges of the same and inwardly of the pivoted bars 9 of the lazy-tongs supporting device. The cross-rod 15 therefore is adapted to slide along the under edges of the

strips 19 during angular adjustment of the bars 9 and 10. This adjustment of the supporting device may be obtained by operation of the shaft 16, which is provided upon one end thereof with a crank 20 having a handle 21 by which it may be rotated manually. A ratchet 22 is provided upon the shaft adjacent to the crank for engagement by a releasable pawl 23, which latter is pivotally mounted upon the adjacent flange of the top. The operation of this device will be described more fully hereinafter.

Short supporting strips 24 extend along the inner faces of the side rails 3 of the frame 15 immediately below the upper edges thereof and adjacent to the rear rail 5. These strips are adapted to support the lower ends of the side bars 10 of the top-supporting device when in position for maintaining the top at a 20 slight inclination for drafting purposes, as shown particularly in Figs. 7 to 9 inclusive and Fig. 12. A cover or second top 25, as it may be termed, is hinged to the rear edge of the main top as at 26. This second top is 25 adapted normally to overlie the main top and is provided with marginal, depending flanges 27 which are adapted to embrace the edges of the last-named top. This second top is adapted to rest flat upon the main top when 30 the table is used for library or sketching purposes, as shown in Figs. 1 to 3 inclusive and 10 and 11, respectively, but is adapted to be raised into a substantially vertical position for use as a holder for drawings, blue prints, 35 or other data which are being followed in the drafting operation. Securing hooks 28 are pivotally mounted upon the front legs of the frame adjacent to the upper ends thereof for engagement with the eye members 29 carried 40 by the side bars 9 of the top-supporting device when the said bars are vertically disposed to maintain the top in position for sketching, as shown particularly in Fig. 11.

The front rail of the frame body is provided with a drawer opening 30 for the reception of a removable drawer 31 which is adapted, when closed, to extend between the side bars of the top-supporting device. This drawer is adapted for use in storing drawing 50 appliances and materials.

The different positions and adjustments of the table will now be described. In Figs. 1 to 3 inclusive, the main top is shown in its horizontal position, resting upon the frame 55 of the table, and the second top or cover is shown in its closed position wherein it lies flat upon the main top. The table in this form is adapted for use as an ordinary library table. When it is desired to use the 60 table, however, for drafting or other purposes, with its main top elevated, but still horizontally disposed, the operating crank is turned in clockwise direction, whereupon the upper ends of the side bars 9 and 10 of the 65 supporting device will be drawn toward each

other so as to raise the top to the desired elevation wherein it will be locked by the pawl and ratchet device. Owing to the fact that the flexible winding members pass up over the guide bar 18, the leverage will be increased so as to minimize the force required in raising the top. As shown in these figures of drawing, the second, hinged top is swung back to its open position.

When it is desired to incline the main top 75 of the table to a slight degree, in order to accommodate the same to the position of the draftsman using the table, the top is tilted forwardly, after the side bars 9 and 10 of the supporting device have been adjusted sufficiently to permit the same to clear the supporting strip 24, and then the said bars are expanded by releasing the pawl from engagement with the ratchet until the lower ends of the bars 10 bear 80 upon the said supporting strips. While the top is supported effectively in this inclined position, as shown particularly in Figs. 7 to 9 inclusive, it may be adjusted 85 toward or away from the operator by manipulation of the crank.

When it is desired to use the table for sketching purposes, wherein it is essential that the top shall be nearly vertical, the second top 25 is closed upon the main top 95 and the latter is tilted farther so as to bring the side bars 9 into vertical positions, wherein they may be secured by means of the hooks 28. This position of the device is shown in Figs. 10 and 11.

From the foregoing description, taken in connection with the accompanying drawings, it should be apparent that I have provided a table, which may be used efficiently 105 in various capacities and which is extremely simple in its construction, so as to be easily adjustable, durable, and inexpensive in the cost of manufacture.

What is claimed is:

1. A table of the class described comprising a frame consisting of supporting legs and top rails connecting the same, a top movably mounted upon the frame, a supporting device for the top including side pairs of medially pivoted bars, adjacent 110 ends of corresponding bars of both pairs being pivotally connected with the side rails of the frame, the corresponding ends of the other bars being pivotally connected with the top, the opposite ends of the first-named bars being frictionally engaged with the top, the side rails of the frame being constructed to provide horizontal ledges adapted to support the opposite ends of the last-named bars of both pairs, means by which 115 the relatively movable bars of each pair may be adjusted angularly, and short, horizontally disposed supporting strips mounted upon the side rails of the frame above the said ledges and in spaced relation to the 120

125

130

pivoted ends of the side bars connected with the frame for supporting engagement with the free ends of the other bars.

2. A table of the class described comprising a frame consisting of supporting legs and top rails connecting the same, a top movably mounted upon the frame, a supporting device for the top including side pairs of medially pivoted bars, adjacent ends 10 of corresponding bars of both pairs being pivotally connected with the side rails of the frame, the corresponding ends of the other bars being pivotally connected with the top, the opposite ends of the first-named 15 bars being frictionally engaged with the top, the side rails of the frame being constructed to provide horizontal ledges adapted to support the opposite ends of the last-named bars of both pairs, means by which 20 the relatively movable bars of each pair may be adjusted angularly, and detachable means for securing the side bars connected with the frame in vertically disposed position.
- 25 3. A table of the class described comprising a frame consisting of supporting legs and top rails connecting the same, a top removably mounted upon the frame, a supporting device for the top including side

pairs of medially pivoted bars, adjacent 30 ends of corresponding bars of both pairs being pivotally connected with the side rails of the frame, the corresponding ends of the other bars being pivotally connected with the top, the opposite ends of the first-named 35 bars being frictionally engaged with the top, the side rails of the frame being constructed to provide horizontal ledges adapted to support the opposite ends of the last-mentioned bars of both pairs, and means by 40 which the relatively movable bars of each pair may be adjusted angularly including a transverse operating shaft journaled in the top, means for rotating said shaft, a flexible member connecting the free end of 45 each side bar which is pivoted to the frame with the shaft being adapted to be wound thereon, means for guiding said flexible member, and detachable means for securing the side bars connected with the frame in 50 vertical position.

In testimony whereof I affix my signature in presence of two witnesses.
